Patented Feb. 2, 1915.

UNITED STATES PATENT OFFICE.

JOHN J. AYLWARD, OF BROOKLYN, NEW YORK.

SIGNALING AND INDICATING DEVICE.

1,126,681.

Specification of Letters Patent.

Patented Feb. 2, 1915.

Application filed March 4, 1914. Serial No. 822,329.

To all whom it may concern:

Be it known that I, JOHN J. AYLWARD, a citizen of the United States, and a resident of the borough of Brooklyn, in the county 5 of Kings and State of New York, have invented certain new and useful Improvements in Signaling and Indicating Devices, of which the following is a specification.

This invention relates particularly to electrically controlled signal and indicating apparatus.

One of the objects of the invention is to produce an improved device of the class above referred to, which shall be composed 15 of but few parts and be capable of transmitting motion in a reliable manner, such as is required for instance, in operating secondary clocks, floor indicating systems for elevators, engine-room telegraphs, and other 20 appliances employing intermittently actuated indicators.

Another object is to provide a device readily adapted to carry an indicating member of any desirable design, for example, an 25 index hand co-acting with a dial, or a drum with symbols, or other elements of similar character.

A further object is the provision of a frame for housing and carrying the component parts of the device, which shall be 30 efficient and at the same time susceptible of being manufactured at low cost.

Further objects and advantages of the invention will become apparent as the specification proceeds.

With the said objects in view, the invention consists of the arrangements and combinations of parts hereinafter described, pointed out in the subjoined claims, and 40 illustrated in their preferred embodiment by the annexed drawings, in which:—

Figure 1, is a composite plan view and section of the device, partly broken away; Fig. 2 is a fragmentary front elevation and 45 section of the same; Fig. 3 is a fragmentary sectional elevation representing a modified construction of the device, and Fig. 4 is a front view with parts shown in section of another modification.

50 In these views, the reference numeral "5" designates the base of the device, which may consist of a circular plate, as shown in Fig. 1, and is preferably placed inside a casing 6, to the bottom of which it can be conveniently, as well as detachably secured by 55 means of screws 7.

On the surface of the base plate 5 are produced a plurality of housing members or sockets 9, which are open outwardly with relation to the circumference of the plate and are disposed at equal distances apart thereover. These sockets may be cast integral with the plate, and are designed to contain each an electro-magnet 11, of the solenoid type. By preference, three sockets 60 9 are utilized in the form of the invention herein illustrated. The said electro-magnet has a fixed core 12, extending axially from the outer open end of its socket 9, to the inner end thereof, which is closed, excepting 65 a central aperture wherein a reduced portion 13 of the said core is received by a screw thread connection.

A spindle 15 is loosely fitted in a central longitudinal bore of the fixed core 12, 70 through which it is adapted to slide. This spindle acts as a plunger for a discoidal armature 16, located transversely of the open end of the socket 9, from which the said armature is mechanically and normally projected by means of a helical spring 17, coiled around the said spindle and lodged within an enlarged portion 18 of the said bore. The latter named portion of the bore is 75 made conical as at 19, to receive a correspondingly shaped member or appendage 20, formed or placed on the spindle at or near the point thereof with the armature. It will be observed that the conical member 20, entering the recess 19 of same outline, operates to close or reduce the gap at the armature end of the fixed core and thereby lessen 80 interference with the magnetic flux or lines of force. Within the triangular space comprised between the inner ends of the said 85 sockets 9, is placed an upright shaft 23, stepped at its lower end in the base 5 and having its upper end similarly journaled in a plate 24, which overlies the said inner ends of the sockets and is supported by flat 90 bosses or blocks 25 produced thereon. An axially offset part which is here shown in the shape of an eccentric cam 26 is formed or rigidly attached to the shaft 23, in the 95 projecting planes of the several spindles 15 and in position to be acted upon by them intermittently in rotation. The shaft 23 is 100 intended to impart motion to the indicating member of the device, either directly or indirectly, as hereinafter described.

Fig. 2 shows an efficient method of operating the indicating element from the shaft 23

through the medium of a train of gears which may be either spur or any other suitable kind. In this view, as well as in Fig. 1 the indicating member is in the form of an index hand 30, arranged to revolve over a dial 31, in a well known manner. This dial is secured to an annular flange 31^a, the latter being held in place by a rim 32 depending from the cover 33 of the before mentioned casing 6. The said cover has a glazed aperture through which the hand 30 and the symbols on the dial 31 pointed out thereby may be observed. The gearing between said index hand and the upright shaft 23 is here shown as comprising a fixed pinion 34 on the upper end of the latter, in mesh with a gear-wheel 35, loosely revolving on a pin 36 passing through the plate 24, a pinion 37 rigidly connected to said gear-wheel, and a second gear wheel 38, to which is fastened the inner end of the hand 30 both of these latter named elements being loosely mounted upon the upper end of the shaft 23. The pin 36 is threaded into one of the bosses or blocks 25 under the plate 24, which it helps to maintain firmly in position. It is further formed with a broad head 39, serving to keep in their proper places the gear wheel 35 and pinion 37 of which it constitutes the pivot. The desired number of graduations on the dial 31 determines the ratio of gearing to employ, and although there may be but three impulses imparted to the shaft for a complete revolution, the gearing can be so proportioned as to secure always the required number of indications on the dial, for example, all the intervals representing hours and minutes on the face of a secondary clock.

40 An electrical impulse-transmitting device, of suitable type to rotate the aforesaid cam-bearing shaft 23 and the thereto connected indicating member 30, through the agency of the previously described armatures and plungers thereof, is illustrated at 40, Fig. 1. As there shown the said transmitter comprises a source of electric energy 41, one pole of which is connected with a pivoted switch-controller 42, by a wire 43, and the other pole having a wire 44, common to all the electro-magnets. Contact points *a* *b* *c* are also connected by wires 45, 46, 47 to the several magnets, and to one another in pairs by intermediate wires 48, 49, 50. The connections are such it will be noticed, that as the controller arm is moved over the contact-points, it will successively close and open the various circuits in which the electromagnets are located, and by energizing the latter, will cause them to draw the armatures 16 toward the open ends of the sockets 9, consecutively. As each armature moves inward, the plunger 15 thereof is slid axially through the core 12, against the spring 17, and being thrust out of the closed

end of the corresponding socket 9, meets the cam 26 of the shaft 23. The impact of the rounded inner end of the plunger upon the cam causes it to revolve the shaft partly, and simultaneously to shift the cam into the path of the next plunger. Thus, the cam bearing shaft is turned by a series of impacts from disconnected plungers impinging upon it one after another in succession.

In order to limit the outward movement of the armatures and their plungers, as they are being repelled by the springs, when the electric current is cut out of the magnets, the outer ends of the spindles 15, constituting the said plungers, are capped with rubber bumpers 51, which intervene between the several armatures and the adjacent walls of the casing 6. These bumpers or cushions save the armatures and spindles from actual contact with the casing and deaden the noise which otherwise might be produced by the same.

A detent which may be in the nature of a spring pressed stop 55 is preferably employed to check over rotation of the shaft 23, as it is being actuated by repeated impacts from the armature plungers against the cam 26. This stop is conveniently placed in a barrel 56, formed on the surface of the base plate 5, and co-acts with a series of peripheral notches or indentations 57 around the shaft 23.

As shown in the modified construction of Fig. 3, the indicating member may well be connected up directly with the aforesaid shaft. In this view, it simply consists of a hollow drum 30^a, rigidly attached to the upper end of the shaft 23, and bearing symbols, as "2" etc., displayed on its outer circumference. Such symbols may be seen through an aperture 62, in one side of the casing 6. It will be understood that this drum 30^a, could as well be substituted for the hand 30 in Figs. 1 and 2, bearing the same relation to the shaft 23, and being controlled by a similar train of gears. It is obvious that several sets of compound gearing could also be used. Fig. 3 shows also a modified form of detent for the rotary shaft 23, the same being formed with the plate 24^a, through which the said shaft passes, a barrel 56^a, formed thereunder, a coiled spring 68 lodged in said barrel, and a ball 55^a, pressed by said coil-spring into corresponding cavities 57 in the periphery of the shaft. Further in this view, the device for limiting the outward movement of the armature 16 is here shown attached, as at 51^a to the wall of the casing 6 instead of to the outer end of the spindle 15, in order to clear the drum 30^a.

The modification of the invention shown in Fig. 4 illustrates how a drum-carrying counter 70 may be connected up with the impact mechanism. Here also the walls 6^a of the outer casing have been represented as

formed integral with the sockets 9^a and the base 5^a. Further, these sockets 9^a have been extended sufficiently to inclose the outer ends of the armature 16^a, and the cover plate 6^b, applied thereover prevents moisture, dirt or other foreign matter from entering. The counter 70 is shown as carried by the cover 33^a, the hub of the gear-wheel 38^b extending through an opening in the same and providing

10 a suitable coupling means 71 for the driving spindle of the counter. In other respects the elements and their combinations in this view are substantially the same as described with reference to Fig. 2.

15 It is understood that when this improved signaling apparatus is to be used in connection with an elevator, the controller arm of the transmitting device will be arranged to synchronize with the movements of the car or cage, while the several sets of contact points are placed to correspond to the different landings, so that as each floor is being approached the arm will sweep over the contact point or points for that particular floor 20 and set the appropriate signals.

25 While I have shown and described certain preferred embodiments of my device, it will be understood that changes in the form, arrangements, size, proportions and details thereof may be made without departing from the scope of the invention as defined by the appended claims.

Having described my invention what I claim and desire to secure by Letters Patent is:—

35 1. A signaling device comprising an indicating member, a rotary shaft therefor, a plurality of plungers operating to turn said shaft by successive impacts thereupon, and means for actuating said plungers.

40 2. A signal and indicating device comprising a support, a series of outwardly facing electro-magnets equidistant thereon, a rotary shaft located between said magnets, plungers slidable through the several magnets inwardly toward said shaft and adapted to rotate the same by successive impacts thereagainst, an indicating member operatively connected up with said shaft, and means for actuating said plungers from the outer ends of the magnets consecutively.

45 3. A signaling device comprising an indicating member, a revoluble shaft connected therewith, a plurality of electromagnets disposed at regular intervals apart about said shaft, disconnected plungers slidable through the several magnets inwardly toward the shaft and adapted to rotate the latter by impact, armatures drawn by said magnets at the ends thereof remote from said shaft to actuate said plungers, means for energizing the magnets one after the other, and means for repelling the plungers after demagnetization.

50 4. A signal and indicating device com-

prising a rotary shaft, a member moved thereby, a plurality of electro-magnets equidistantly disposed around said shaft, a fixed core in each magnet having an axial bore, a plunger slidable axially through said core 70 so as to impinge upon said shaft, means for sliding said plunger, and means for repelling the latter subsequently to its impact upon the shaft.

5. A signaling device comprising an indicating member, a rotary shaft therefor, a series of electromagnets about said shaft, a fixed core in each magnet having an axial bore with a partial enlargement, a plunger slidable through said core so as to impinge 75 upon said shaft, a repelling spring coiled around said plunger within said enlargement of the bore, and means for sliding the plunger against the action of said spring.

6. A signaling device comprising an indicating member, a rotary shaft actuating the same, a series of electromagnets disposed around said shaft, a fixed core in each magnet having an axial bore with a conical enlargement at one end, a plunger axially 80 slidable through said core so as to impinge against said shaft, an armature carried by said plunger acted upon by said magnet, and a conical appendage on the plunger adapted to enter said enlargement and 85 thereby close or reduce the gap between the plunger and the adjacent walls of the magnet core.

7. A signaling device comprising an indicating member, a rotary shaft connected 100 therewith, a plurality of electro-magnets disposed around said shaft, a fixed core in each magnet having an axial bore, a plunger slidable through said bore so as to impinge against said shaft, an armature carried by 105 said plunger, means for energizing the magnet to attract said armature, means to repel the plunger with its said armature after demagnetization, and a limit stop on the outer end of the plunger.

8. A signaling device comprising an indicating member, a cam-bearing shaft adapted to rotate the same, magnetic supports located around said shaft, a plunger slidable through each support toward the 115 shaft to rotate the latter by impact against said cam, means for actuating the several plungers consecutively, and means for repelling each plunger after impact thereof upon the cam of the shaft.

9. An intermittently operated device comprising a shaft, an indicating element connected up therewith, an axially offset part carried by said shaft, a plurality of plungers operating to turn the shaft by successive impacts upon said part, and means for actuating said plungers.

10. A signal and indicating device comprising a base, a shaft in the same, a series of supports surrounding said shaft, plun-

- gers slidable in said supports, an axially offset part on the shaft operating to turn the latter by successive impacts received from said plungers, means for repelling each plunger after impact, a bearing member at the other end of said shaft carried by said supports, an indicating member, and gearing operatively connecting up the shaft with said member.
- 10 11. A signal and indicating device comprising a rotary shaft, a series of magnetic supports surrounding the same, plungers slidable in said supports toward said shaft, an axially offset part on the latter actuated by successive impacts from said plungers, an indicating member moved by the shaft, and a detent operating to hold the shaft between impacts.

12. A signal indicating device comprising a support, sockets carried thereby, an electro-magnet in each socket, armature-carrying plungers actuated by the several magnets, a shaft journaled in said support and having an axially offset part in the plane of said plungers, the latter being free from the shaft and operating one after the other to rotate the same partially by impact upon said offset part, and a member connected up with said shaft.

Signed at the borough of Manhattan in the county of New York and State of New York this 28th day of February A. D. 1914.

JOHN J. AYLWARD.
